UNITED STATES PATENT OFFICE.

JAMES H. RAND, OF NORTH TONAWANDA, NEW YORK, ASSIGNOR TO RAND KARDEX COMPANY, INC., OF NORTH TONAWANDA, NEW YORK, A CORPORATION OF DELAWARE.

INDEX DEVICE.

Application filed December 26, 1923. Serial No. 682,640.

This invention relates to index devices of the type in which a series of cards are interchangeably mounted on a frame in overlapping relationship so that any card may be viewed, or removed, by swinging the superposed cards from their normal positions thereover.

Devices of this character are intended for use where the index subject-matter must be changed frequently; for example, when used in factories to indicate the progress of orders the indicia is ordinarily changed or supplemented whenever the order progresses from one department to another so that the index always shows the status of the work. For permanency the indicia must be written with ink, and owing to the restricted space it is difficult to blot the writing without smearing the ink in moving the blotter into position between the juxtaposed cards and holders. Consequently it has been customary to remove a card to change or supplement the indicia thereon. This is time-consuming and frequently results in a card being replaced in the wrong position.

The object of the present invention is to provide an index device in which the writing on a card is automatically blotted by the next adjacent card holder when the cards are permitted to swing into normal position after indicia have been added, thereby avoiding the necessity of removing the cards from their holders for writing thereon or, if the cards are removed for this purpose, avoiding the necessity of blotting before the cards are slipped back into place.

For the purpose of illustration two concrete embodiments of the invention are shown in the accompanying drawings, in which:

Fig. 1 is a front elevation of a typical index frame carrying a series of overlapping card holders, parts being broken away;

Fig. 2 is a rear view of one form of holder;

Fig. 3 a face view of part of the holder shown in Fig. 2; and

Fig. 4 is a rear view of another form of holder.

The index frame shown in Fig. 1 comprises an upright part 1 having pintles 2 at its upper and lower ends to swing in a stand, top and bottom arms 3 extending horizontally from the rod 1, a side piece 4 connecting the outer ends of the arms 3 and channel

members 5 adapted to support the index 55 holders detachably.

The holder shown in Fig. 2 comprises a supporting card 6 having a rail 7 fast to its upper edge and a sheath 8 of celluloid or the like, U-shaped in cross section, fitting over its lower edge, the sheath being held on the card by means of marginal staples 9 and a central staple 10, the marginal staples extending through both sides of the sheath and the central staple extending only through the rear side of the sheath. A blotter 11 is slipped into the pocket beneath the card 6 and the back of the sheath 8, a recess 12 being provided in the lower margin of the blotter to accommodate the central staple 10. 70

The holder shown in Fig. 4 comprises a supporting card 6', a top rail 7', a bottom sheath 8' as in Fig. 2, but the blotter 11' is permanently mounted instead of detachably mounted as in Fig. 2, the staples 9' extending through the card 6', both sides of the sheath 8' and through blotter 11', and the staple 10' extending through sheath 6', blotter 11' and the rear side of the sheath 8'. If desired the blotter may be glued to the back 80 of supporting card 6' or the supporting card may be in the form of a blotter either with or without a writing surface on its front side. The index indicia may be written directly upon the front of the cards 6' (or 6) 85 or upon cards 16 fitted in the pockets between the cards 6' (or 6) and the fronts of the sheaths 8.

The card holders are mounted in the frame shown in Fig. 1 by inserting the projecting 90 ends of the rails into the channels 5, the rails and cards being flexed transversely to permit this insertion. The junction between the rail 7 and the card 6 is flexible so that the cards may be swung upwardly to expose 95 a particular card to be inspected or altered. By virtue of the position of the blotter on the backs of the cards, the writing on any particular card is automatically blotted when the holders are permitted to swing 100 back into normal position.

I claim:

1. An index device comprising a frame, a series of cards interchangeably mounted on said frame in overlapping relationship, and a blotter mounted upon the back of each card to blot the front of the next underlying card. 105

2. An index device comprising a frame, a series of card holders interchangeably mounted on said frame in overlapping relationship, each holder having a sheath along its exposed edge, an index card in each sheath, and a blotter between the card and the back of the sheath.
3. An index holder comprising a card

having a supporting rail fast to one edge and a sheath over the opposite edge, and a blotter mounted behind said card with its margin within said sheath.

Signed by me at Boston, Massachusetts, this 18th day of December 1923.

JAMES H. RAND.
